(57) **CLAIM**

The ornamental design for a knife and badge holder, as shown and described.

DESCRIPTION

FIG. 1 is a perspective view of a knife and badge holder showing our new design;

FIG. 2 is a front elevational view thereof;

FIG. 3 is a right-side elevational view thereof, the left side being a mirror image thereof;

FIG. 4 is a rear elevational view thereof;

FIG. 5 is a top plan view thereof; and,

FIG. 6 is a bottom plan view thereof.

The dashed dot line of a knife blade and badge shown in the drawings form no part of the claimed design.
